US00D681835S

(12) **United States Design Patent**
Stephan et al.

(10) **Patent No.:** **US D681,835 S**
(45) **Date of Patent:** **** May 7, 2013**

(54) **CONTAINER ASSEMBLY**

(75) Inventors: **Gary R. Stephan**, Seven Hills, OH (US); **Craig Saunders**, Rocky River, OH (US); **Evan Spirk**, Gates Mills, OH (US); **Jeffrey Kalman**, Cleveland Heights, OH (US); **David Boll**, Avon, OH (US); **Anthony S. Zuccaro**, Chesterland, OH (US)

(73) Assignee: **Abbott Laboratories**, Abbott Park, IL (US)

(**) Term: **14 Years**

(21) Appl. No.: **29/403,149**

(22) Filed: **Oct. 1, 2011**

Related U.S. Application Data

(63) Continuation-in-part of application No. 29/369,869, filed on Sep. 14, 2010.

(51) **LOC (9) Cl.** **07-01**

(52) **U.S. Cl.**

USPC **D24/197**

(58) **Field of Classification Search** D24/193-198; D9/500, 503-504, 547, 444-445, 454; D7/510-511, D7/533-534; 215/6, 10, 11.1-11.6, 12.1, 215/13.1, 255-256, 378; 220/703, 720

(74) *Attorney, Agent, or Firm* — McAndrews, Held & Malloy, Ltd.

CLAIM

The ornamental design for a container assembly, as shown and described.

DESCRIPTION

FIG. 1 is a front perspective view of a container assembly showing our new design;

FIG. 2 is a rear perspective view thereof;

FIG. 3 is a left side elevation view thereof,

FIG. 4 is a right side elevation view thereof;

FIG. 5 is a front elevation view thereof, the rear elevation being a mirror image;

FIG. 6 is a top plan view thereof; and,

FIG. 7 is a bottom plan view thereof.

The broken lines are for the purpose of illustrating portions of the container assembly and form no part of the claimed design.
